UNITED STATES PATENT OFFICE

CHARLES P. MADSEN, OF NEW YORK, N. Y., ASSIGNOR, BY MESNE ASSIGNMENTS, TO
WILLIAM W. VARNEY, OF BALTIMORE, MARYLAND

METHOD OF SUPPORTING PHONOGRAPH REPRODUCING SYSTEMS

Application filed February 2, 1925. Serial No. 6,415.

The object of my invention is to position the operating point of a phonograph reproducer so that it shall vibrate in as near the same plane as the producing point did in making the record as is possible.

A further object of my invention is to position the reproducer of a phonograph so as to bring the least side thrust of the reproducer needle on the record consistent with keeping it engaged and maintaining said side thrust as near uniform as possible throughout the various convolutions of the record.

A further object of my invention is to position the plane of vibration of the reproducing means of a phonograph as near a tangent or radial respectively as the case may be, depending upon the type used as practicable, maintaining substantially equal variations at the extreme outer and inner convolutions of a disc record to be played.

With the foregoing and other objects in view, my invention consists of the methods employed, combination and arrangement of reproducing systems, apparatus and means as hereinafter specifically provided and illustrated in the accompanying drawings, wherein is shown the preferred embodiment of my invention as applied to a phonograph, but it is understood that changes, variations and modifications may be resorted to which come within the scope of the claims hereunto appended.

It is well known that the reproducing system in any phonograph should not only be able to follow the groove or the cut of a record with the least possible resistance and also to allow for the variations or mechanical imperfections in the record, but should approximate the same geometrical relation with every groove of the record during playing. In the old cylinder machine, as, for instance, the Edison type, it was customary to drive the reproducing system across the face of the cylinder with a solid collar actuated by a nut and thread of the same pitch as the cut in the record. In this manner the relation of the reproducer to the record remained quite constant and fixed at all points.

In the more modern disc record machines, however, such a device has been found to be

too clumsy and expensive, and it has been customary to support the reproducer at the end of a tube, called the tone arm, and swing it from a pivoted point at some distance from the record, as illustrated in Figure 1, as shown 55 in the diagrammatic drawing.

In this figure (Figure 1) the line AB represents a radius to the center of the record and C a pivot point at some distance from the record, usually a distance at least equal to the 60 diameter of the record. The pivot is usually so placed that a line drawn from it to the radius AB will be at right angles to AB at a point about in the center of the musical 65 grooves, that is, midway between the inner and outer circles of the record. The point E represents the position of the needle point at the commencement of playing and the point D at the end. It will be seen that the needle then is tangent to the record groove only when 70 it is at the point O. At the commencement of playing at point E there is an appreciable angle formed with the tangent depending on the position of the point C, and when at point D the angle to the tangent is still greater, 75 the degree of the angle from tangency depending, of course, upon the position of point C.

In the specific case given the distance from C to O is that of the diameter of the record, 80° usually ten inches. Then the angle from tangency at E will be about 7 degrees and that at D about twelve degrees. This condition results in two difficulties: First, it changes the timbre or tone quality of the reproduction as the playing progresses, and second, it increases the wear on the record, particularly toward the end or inner circle.

I have discovered a relation which permits of swinging a reproducing system from a 90 pivot at substantially the same distance from the center of the record as the diameter of the record and which still maintains the diaphragm or needle rocker in substantial tangency to every groove on the record.

Referring now to Figure 2: AB again represents a radius from the center through both concentric circles. CD represents a line at right angles to AB, commencing from the inner musical groove. This line now is tan- 100

gent to the inner convolution since it is at right angles to the radius from the center. At the point of intersection of the radius with the outer convolution at E I also erect a right angle, line FE of the same length. This now also is tangent. I find that if I now support an L-shape tone arm or supporting lever at C, whose outer leg is equal to CF and the other leg equal to FE, with the reproducer at E, a substantially tangent position of the rocker needle will be maintained to every convolution. The rocker needle or diaphragm is tangent at the outer convolution by definition. If now as the point E moves across the record toward D, it also goes forward so that it is contacting on a different radius in every convolution until when it reaches G, if a line be drawn from A through it and a right angle to said line it will be found to substantially coincide with a tangent to the convolution at point G.

In actual construction it is not necessary to make the support arm in the form shown in this figure, but one may instead use that shown in Figure 3, in which case the pivot is still C on the same parallelogram. The lever, instead of proceeding from C to F is substantially the diagonal of the parallelogram, but the support means for the needle is so arranged at the end that in the case of an ordinary reproducer the diaphragm is parallel with the line EF.

Referring to Fig. 3, with the tone arm pivoted at C and the diaphragm tangent at point E to the convolutions at that point when swung over to the point G, the diaphragm is about 5 degrees from being tangent to the convolutions at that point. This can be overcome and a perfect tangent had at G, if desired, by fulcruming the arm (that is, move point C to C¹) at C¹; thus correcting the variation of 5 degrees above mentioned; but this will not produce a true tangent of the diaphragm to the outer convolution when swung over. If, however, we retain the fulcrum C and slightly lengthen the arm so that the diaphragm is tangent at G¹, then when the diaphragm is swung to the outer convolution it will be within 2 degrees of tangent to said convolution. In the specific case the lengthening of the line FE amounts to about $\frac{1}{8}$ inch. In practice this latter method works the better. The outer circle is so much larger than the inner one that this slight lack of tangency has no appreciable effect as there will be a tendency then to steady the needle against one side of the groove. This method reduces the side thrust.

If the parallelogram figure of Fig. 2 be viewed as a force diagram, it will be seen that there is a resultant of forces inward toward the center of the record, which is proportional to the length of line CF to line FE. It is found by measurement that under ordinary conditions with a reproducer system having

the usual weight of six ounces that the forward pull or force along the line FE amounts to about one and two-tenth ounces when the platen is revolving clock-wise and the pull is longitudinal from fulcrum C. It therefore follows that if the line FE is ten inches long and the line CF is two and a half inches long that the side thrust of the needle at F is about one-fourth of one and two-tenth ounces, or slightly under one-fourth of an ounce. This slight side thrust is of an advantage because it insures the needle hugging continually one side of the record groove. The reason this is an advantage is that the steel needles commonly used do not perfectly fit the groove. There is consequently a slight loss of motion when the groove swings the needle sideways. If, however, this side thrust is too great, it will break down the grooves of the record. I have found, however, that the relation given above produces a firmer reproduction and does not wear the record excessively.

If the first method of location is used, that is moving C to C¹ in Figure 3 were used, the tendency is to increase the side thrust. If the point C is nearer to the line AB than the diameter of the record, this side thrust is also too greatly increased.

Referring to the drawings illustrating my invention, I have already discussed Figures 1, 2 and 3. Figure 4 is a plan view of a phonograph, the supporting arm of which is positioned in accordance with my improved system as herein described; Fig. 5 shows a modified form of the phonograph reproducer shown in Fig. 4, adapted for reproducing from "hill and dale" records, the plane of operation of the reproducer being at right angles to that shown in Fig. 4; Figure 6 shows a plan view of a phonograph of well-known construction, having a tone arm, the fulcrum of which tone arm has been positioned in accordance with my improved system so that the diaphragm is substantially tangent both to the inner and outer convolutions of the record; Fig. 7 is a view in elevation, partly in section, of a phonograph shown in Fig. 6; Fig. 8 is a view of a fragmentary detail on an enlarged scale of the reproducer shown in Fig. 4, looking in the direction of the arrow upon the face of the same.

Having thus described my invention, what I claim and desire to secure by Letters Patent is:

1. In an organized phonograph of the disc type a supporting arm for the reproducer in use whereby the stylus of the reproducer operates in a vertical plane tangent to the convolution of the groove of the record, or within the limit of four degrees thereof at the inner convolution of the disc record in position for playing in said phonograph, and said stylus operating in a plane within the limit of ten degrees of the vertical plane tangent

to the outer convolution of the groove of said disc record, the fulcrum of said supporting arm being a common center and relatively fixed for both positions.

5 2. In an organized phonograph of the disc type a supporting arm for the reproducer in use whereby the diaphragm of the reproducer operates in a vertical plane tangent to the convolution of the groove of the record, or within the limit of four degrees thereof at the inner convolution of the disc record in position for playing in said phonograph, and said diaphragm operating in a plane within the limit of ten degrees of the vertical plane tangent to the outer convolution of the groove of said disc record, the fulcrum of said supporting arm being a common center and relatively fixed for both positions.

3. In an organized phonograph of the disc type a supporting arm for the reproducer in use whereby the stylus of the reproducer operates in a plane at right angles to the vertical plane tangent to the convolution of the groove of the record, or within the limit of four degrees thereof at the inner convolution of the disc record in position for playing in said phonograph, and said stylus operating in a plane within the limit of ten degrees of the vertical plane at right angles to the plane tangent to the outer convolution of the groove of said disc record, the fulcrum of said supporting arm being a common center and relatively fixed for both positions.

4. In an organized phonograph of the disc type a supporting arm for the reproducer in use whereby the diaphragm of the reproducer operates in a plane at right angles to the vertical plane tangent to the convolution of the groove of the record, or within the limit of four degrees thereof at the inner convolution of the disc record in position for playing in said phonograph, and said diaphragm operating in a plane within the limit of ten degrees of the vertical plane at right angles to the plane tangent to the outer convolution of the groove of said disc record, the fulcrum of said supporting arm being a common center and relatively fixed for both positions.

CHARLES P. MADSEN.
